CLUSTER BOMB RACK

Fred Schultze, Rockaway, N. J.

Application September 18, 1942, Serial No. 458,882

5 Claims. (Cl. 89—1.5)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to bomb racks of the cluster type and more particularly to an improved releasing device for such bomb racks.

It is an object of this invention to improve the ease and certainty with which the individual bombs may be separated as the rack is dropped without impairing the security of the connection prior to release of the rack or in event it appears desirable to drop the rack and bombs in a safe unarmed condition.

The exact nature of the invention as well as other objects and advantages thereof will clearly appear from a description of a preferred embodiment as shown in the accompanying drawing in which:

Fig. 1 is an end elevational view partly in section of a cluster bomb rack including my improved releasing device.

Fig. 2 is a top plan view of my releasing device broken out of the cluster bomb rack.

Fig. 3 is an oblique view of my releasing device.

Referring to the drawing by characters of reference the bomb rack shown therein comprises in known manner an upper frame member 1 and a lower frame member 2. These members are provided with spacer plates 3 engaging the neck and tail of each of the individual bombs to secure them against longitudinal movement. The bombs are preferably retained in engagement with the notches in the spacer plates by means of an encircling band 6 of nailless box strapping or similar material which is secured at its end portions to the upper frame member 1.

The securing means for the ends of the band 6 comprises a pair of similar body plates 7 secured to the upper frame member 1 in spaced parallel relation by welding or other convenient means. A bolt 8 is inserted through both plates in substantially parallel relation to the upper frame member and is provided with means such as a slotted shank to engage an end of the band 6 and permit tensioning of the band by rotation of the bolt. A nut 9 and lock washer 10 are provided to secure the bolt against rotation when the band is tensioned.

The body plates are provided on the opposite side of the upper frame member with a lock finger pivot screw 11 and a pair of lock fingers 12 which are swingable on the pivot screw 11 and are each provided with a finger 13 capable of engaging the upper frame member and with a

notch 14 in which the strap clamp 15 may be engaged. The strap clamp 15 comprises an elongated member which is preferably bent to accommodate itself to the upper surface of the body plates and is provided with means between its ends to receive the band 6 in permanent non-slipping relation. Such means may conveniently consist of a pair of slots 16 through which the band may be inserted and brought back in position to bear upon itself. At an end 17 the strap clamp is of sufficient width to engage the notch 14 of each of the lock fingers while the other end 18 of the strap clamp is preferably narrow enough to be received between the upward extensions of the body plates and retained therebetween by means of a cotter pin 19 inserted through matching holes in the body plates. An additional pair of holes 20 is provided to receive an arming wire 21.

In assembling the cluster the band 6 may first be engaged with the bolt 8 and then passed around the bombs which are shown in phantom lines in Fig. 1. The strap clamp is then engaged in the notches in the lock finger and swung about the pivot to bring the lock finger into engagement with the upper frame member and the strap clamp into position to be secured by the cotter pin 19. The band may then be tightened by rotation of the bolt 8 and secured in a tight condition by screwing down the nut 9 upon the lock washer 10. At the time that the cluster rack is assembled in the plane the arming wire 21 is inserted in the holes 20 and the cotter pin withdrawn. Upon dropping the rack the arming wire 21 will be withdrawn in a known manner and the tension in the band 6 will cause the lock fingers to rotate on the lock finger pivot screw, releasing the strap clamp and freeing the individual bombs for independent fall. Springs assembled between the bombs may be used to assist in separation. In case it is desired to jettison the bombs over friendly territory the arming wire may be dropped with the rack in a known manner and the bombs will remain assembled to the rack in safe unarmed condition.

It should be noted that the securing means shown herein cannot be accidentally disengaged in event the tension of the band should be slightly lessened accidentally, as the interlocking engagement of lock finger, strap clamp and body plates will positively prevent the release of any of these parts without first removing both the cotter pin and the arming wire. At the same time the tension in the band acts against the comparatively long lever arm between the notch and the center

of the lock pivot screw which allows a fast and easy releasing action when the arming wire is withdrawn.

I claim:

1. A bomb rack comprising a fixed member, a bomb holding band having one end attached to the fixed member, a latch member articulated to the other end of said band, a finger pivoted to said fixed member and comprising a seat for one end of the latch member, said seat spaced from 10 the finger pivot and facing in a direction opposite the direction of the pull bomb holding band and releasable means on the fixed member for holding the latch member and hence the finger, through its seat, against rotation.

2. A bomb rack comprising a relatively fixed member, a bomb encircling band secured at one end to said member, a pair of spaced plates secured to said fixed member, a lock finger on said plates and rotatable about an axis passing through both plates, a seat on said lock finger spaced outwardly of said axis and facing in a direction opposite the direction of pull of said band, a strap clamp engaged at one end in said seat, means positively connecting the other end of said bomb encircling band to the strap clamp, and releasable means on said plates normally engaging the other end of said strap clamp to prevent movement of said clamp and hence rotation of said lock finger.

3. A bomb rack comprising a relatively fixed member, a band adapted to encircle at least one bomb and secured at one end to said fixed member, a pair of spaced parallel plates secured to said fixed member, a lock finger pivotally mounted on said spaced plates and having an outwardly extending portion provided with a seat facing in a direction opposite the direction of the pull of said band, a strap clamp engageable at one end in said seat, the other end of said clamp being received between the said spaced plates, means positively connecting the other end of said band

to said clamp, and releasable means for securing said other end of the strap clamp between said plates.

4. A bomb rack comprising a relatively fixed member, a pair of spaced parallel plates secured to said member, a bomb encircling band, means on the rack for securing one end of said band, pivoted means extending through said plates, a lock finger rotatable on said pivot means and provided with a seat outwardly of the pivoted means and facing in opposite direction to the direction of pull of the band, a strap clamp, means positively connecting the other end of said band to the strap clamp, one end of said clamp being adapted to engage the seat on the lock finger, said clamp adapted to be swung with the finger to bring the other end of the clamp between the plates, and releasing means to retain said other end of said clamp between said plates.

5. In a bomb rack, releasable retaining means for the bomb, said means comprising a bomb encircling band, a pair of spaced parallel plates secured to the bomb rack, means on the rack for adjustably securing one end of said band, pivot means on said plates, a lock finger rotatably mounted about said pivot means and having an outwardly extending portion forming a seat facing in opposite direction to the direction of pull on said bomb encircling band, said finger having a portion extending in a direction substantially at right angles to said seat portion, a strap clamp having means intermediate its ends positively connecting it to the other end of said band, one end of the clamp being adapted to engage said seat, the clamp and finger being adapted to be swung in unison to bring the finger into engagement with the bomb rack and the other end of said clamp between said plates, and releasable means for retaining said other end of the clamp between the plates.

FRED SCHULTZE.
